His Attorney.

UNITED STATES PATENT OFFICE.

HARRY M. STEVENS, OF SCHENECTADY, NEW YORK, ASSIGNOR TO GENERAL ELECTRIC COMPANY, A CORPORATION OF NEW YORK.

ALTERNATING-CURRENT ELECTROMAGNET.

Application filed October 7, 1921. Serial No. 505,991.

To all whom it may concern:

Be it known that I, HARRY M. STEVENS, a citizen of the United States, residing at Schenectady, in the county of Schenectady, State of New York, have invented certain new and useful Improvements in Alternating-Current Electromagnets, of which the following is a specification.

My invention relates to improvements in electromagnets for alternating current circuits and has for its object the provision of means whereby the operating characteristics of the electromagnet are improved.

It is well known that an electromagnet when operated on an alternating current circuit is noisy. The noise may vary from a slight hum to a chattering noise, due to the fact that the voltage, in periodically passing through zero, allows the armature to recede from the magnet. This noise, however, slight, is objectionable and various methods of overcoming the same have been proposed. One of the commonest methods of overcoming this difficulty is by means of what is known as a "shading coil". The function of this shading coil is to produce an out of phase flux which persists, when the main flux passes through zero, and helps to sustain the armature. Various forms of shading coils have been devised but in general they consist of a copper ring enclosing a portion of the pole face so as to induce an out of phase flux in the area enclosed by the ring.

This shading coil arrangement has been more or less successful where the presence of residual magnetism is not objectionable. In many cases, however, it is essential to eliminate the residual magnetism so that there will be no tendency for the armature to stick when the current is cut off or the energy of the magnet is reduced to the releasing point. It is not difficult to prevent chattering or humming of the armature or moving core if the latter makes a metal to metal contact with the stationary core so as to bring about a condition known as "freezing" between the two magnetic parts. Under this condition, however, there is a decided tendency for the parts to stick together after the magnetizing force is removed. One of the objects of my invention is to provide means whereby, in addition to overcoming the noise, the tendency of the parts to stick due to residual magnetism is overcome.

It has always been assumed that the shaded or out of phase flux traverses the same circuit as the main flux. It, therefore, seemed reasonable to suppose that an air gap in the main magnetic circuit would be effective to prevent residual magnetism in the shaded circuit. I have found, however, that this is not the case in any of the shaded pole constructions which have come under my observation. I have found that the flux of the shaded pole merely traverses a local circuit and that the effect of the residual magnetism can only be avoided by providing air gaps at the points in the local or shaded circuit where the out of phase flux is passing in opposite directions. The provision of such air gaps, however, makes it necessary to insure a greater flux in the shaded circuit and to locate this flux more symmetrically with respect to the main flux than would be the case if there were no air gap. In carrying out my invention, therefore, I provide an arrangement which in addition to affording the necessary air gaps in the local magnetic circuit also insures a sufficient shaded flux symmetrically disposed with relation to the main flux to hold the armature when the main flux passes through zero, thereby not only preventing chattering but also eliminating residual magnetism. Other objects and purposes of my invention will appear in the course of the following specification in which I have shown my invention embodied in concrete form for purposes of illustration.

In the accompanying drawing illustrating my invention embodied in concrete form, Fig. 1 is a sectional view of an electromagnet embodying my improvements; and Fig. 2 is a perspective view of a shaded pole face therefor. Referring first to Fig. 1, the numeral 10 represents an electromagnet intended for operation on alternating current circuits. This magnet is of the solenoid type and provided with a stationary pole face 11, the external magnetic circuit being through the frame constituted by the members 12, 13 and 14, this being the usual construction of an electromagnet of this character. The moving armature or plunger of the electromagnet comprises a rod 15 of magnetic material having at its end a somewhat smaller rod 16, of non-magnetic material, which extends through the stationary pole piece 11.

Between the two rods 15 and 16 is a pole piece 17 which constitutes one of the important features of my invention. This pole piece, which is shown in detail in Fig. 2, 5 comprises a disc of copper or other non-magnetic material which is an electrical conductor, secured to the upper end of the rod 15 so as to cooperate with the stationary pole piece 11. This copper disc in general 10 performs the function of the usual copper ring used in the shading coil construction, that is, it provides a copper path for currents for inducing out of phase flux in the shaded pole area. As a matter of convenience in construction the magnetic members 15, 18, 19, 20, 21, 22 and 23 are in the form of pins or studs which are securely inserted in the copper disc. This disc is slotted at 24 so as to break the continuity of the ring 15 as a whole, thereby preventing heating currents from circulating around the ring as a whole. The disc is also slotted at each 20 one of the pins 18, 20 and 22 so as to break the continuity of the copper circuit surrounding these pins. These pins 18, 20 and 22, therefore, constitute unshaded area. Pins 19, 21 and 23, however, have solid metal around them and, therefore, have out of phase flux induced in them. These 25 shaded pins are symmetrically disposed in the main flux path as shown to produce an equalized attractive effect to hold the armature in stable equilibrium when the main flux passes through zero. It will be noted 30 that the pins or studs do not extend up so as to be flush with the main surface of the copper disc but terminate somewhat short of the surface so that when the disc is in contact with the stationary pole piece 11 35 there will be an air gap between the pole ends of the studs and the stationary pole piece. In the construction shown, this is accomplished by countersinking a ring 25 in the disc having sufficient width to include 40 the pins. The purpose of this air gap is to eliminate residual magnetism. I have found that out of phase flux induced in the shaded portions does not pass around through the main magnetic circuit constituted by the members 12, 13 and 14 but 45 merely forms a local circuit from the studs into the stationary pole piece back of the studs. An air gap at any other portion of the magnetic circuit is therefore not effective 50 to prevent residual magnetism in this local magnetic circuit. I have, therefore, provided this air gap in the local circuit by making the studs short enough so that they do not form a magnetic path between the 55 rod 15 and the stationary pole piece 11. Since an air gap is provided in the local circuit it is necessary to insure that the out of phase flux will be forced across the gap with sufficient intensity to sustain the armature. The purpose of the unshaded portions 60

constituted by studs 18, 20 and 22 is to bring this about. Under normal operation the flux will pass between the studs and the stationary portion and through the outer magnetic circuit. When the main flux approaches zero there will be set up a local flux from one of the shaded portions 19, 21 or 23, through an air gap at the point of egress 70 of the flux to the stationary pole piece and back through an air gap at the point of ingress of the flux into the adjacent non-shaded studs 18, 20 or 22. The presence of the unshaded studs, therefore, affords a better path for the local flux than will be the case if the return path for the flux in the local circuit were not present. When the magnet is deenergized, the relative direction of flux in the shaded and unshaded portions may be such that there is a tendency 80 to form a local circuit or circuits in a path or paths of such low reluctance that the circuits will persist and keep the moving armature attracted at least temporarily, to the stationary pole piece. By introducing an air gap at the points of ingress and egress 85 of the local circuit or circuits through the members, the reluctance of this magnetic path becomes sufficient to prevent the persistence of the circuit. For purposes of illustration I have shown a structure involving 90 three local magnetic circuits, symmetrically disposed with relation to the main flux, but of course more or less of such circuits may be employed without departing from the spirit of my invention. My experience, 95 however, seems to indicate that the number of local magnetic circuits employed may have a bearing upon the operation. Three such circuits seemed to result in better operation than any other number thus far 100 tried although with further experience it might be found that improved operation would result from the use of a different number of circuits.

While I have described my invention as 105 embodied in concrete form for purposes of illustration, it should be understood that I do not limit my invention thereto since various modifications thereof will suggest themselves to those skilled in the art without departing from the spirit of my invention, the scope of which is set forth in the annexed claims.

What I claim as new and desire to secure by Letters Patent of the United States, is:— 110

1. The method of preventing chattering and avoiding residual magnetism in an alternating current magnet having a movable armature which consists in supplying a local out of phase flux symmetrically disposed 115 with relation to the main flux sufficient to hold the armature when the main flux passes through zero and providing an air gap at the points of ingress and egress of the out of phase flux through the armature. 120

2. The method of preventing chattering and avoiding residual magnetism in an alternating current magnet having a movable armature which consists in supplying a plurality of local out of phase flux paths symmetrically disposed with relation to the main flux path sufficient to hold the armature when the main flux passes through zero and providing an air gap at the points of ingress and egress of said paths through the armature.
3. An electromagnet for alternating current circuits having stationary and movable portions forming the main magnetic circuit comprising a plurality of magnetic members included in said circuit and forming a pole face for one of said portions, means for setting up local magnetic circuits through said members and the other portion and air gaps in said circuits.
4. An electromagnet for alternating current circuits having stationary and movable portions forming the main magnetic circuit comprising means associated with the armature for causing a symmetrically disposed local out of phase flux through a portion of the armature and the stationary magnetic pole face of the magnet and an air gap at the points of ingress and egress of said local circuit through the said pole face.
5. The combination with an electromagnet for alternating current circuits and an armature therefor, of a plurality of magnetic members forming the pole piece of the armature, a copper conducting path surrounding said members and air gaps in the magnetic circuit of the members.
6. The combination with an electromagnet for alternating current circuits and an armature therefor, of magnetic members forming a plurality of local out of phase magnetic circuits from the armatures through the stationary portion of the magnets and return and air gaps in said local circuits.
7. The combination with an electromagnet for alternating current circuits and an armature therefor, of a plurality of groups of magnetic members each cooperating with the stationary portion of the magnet to form a local magnetic circuit and air gaps in said local circuits.
8. The combination with an electromagnet for alternating current circuits, an armature therefor, of a pole piece comprising a plurality of pins of magnetic material each embedded in copper which projects beyond the pins to form an air gap.
9. The combination with an electromagnet for alternating current circuits, an armature therefor, of a pole piece comprising a plurality of pins of magnetic material each surrounded by copper and a plurality of similar pins adjacent thereto having no surrounding copper.
10. The combination with an electromagnet for alternating current circuits, an armature therefor, of a pole piece comprising a copper disc and a plurality of pins of magnetic material embedded therein and having less depth than the disc so as to form an air gap.
11. The combination with an electromagnet for alternating current circuits, an armature therefor, of a pole piece comprising a copper disc and a plurality of pins of magnetic material inserted therein certain of which are surrounded by copper while the remainder are not so surrounded.
12. The combination with an electromagnet for alternating current circuits, an armature therefor, of a pole piece comprising a copper disc and a plurality of pins of magnetic material inserted therein and having less depth than the disc, certain of said pins being surrounded by copper while the remainder are not so surrounded.
13. The combination with an electromagnet for alternating current circuits, an armature therefor, of a pole piece comprising a copper disc, and a plurality of pins of magnetic material inserted therein and having less depth than the disc, certain of said pins being surrounded by copper and alternating with the remaining pins which are not so surrounded.

It witness whereof, I have hereunto set my hand this 6th day of October, 1921.

HARRY M. STEVENS.
